OIL HEATER

Carl S. Reed, New York, N. Y., assignor to The Lummus Company, New York, N. Y., a corporation of Delaware

Application April 2, 1943, Serial No. 481,627

3 Claims. (Cl. 196—116)

This invention relates to a furnace construction and more particularly to an oil heater furnace wherein oil is passed through horizontal tubes positioned in the lower part of the furnace and subjected to heating for the purposes of distillation, cracking or the like.

An object of the invention is to construct an oil heating tube furnace of non-strategic materials at a minimum of cost and substantially devoid of metal fittings and accessories customarily used in constructing oil heating furnaces. In the present construction, the oil tubes are substantially the only metallic parts utilized.

A further object of the invention is to construct an oil heater in the form of an inverted catenary which will be self-sustaining and wherein the entire furnace construction is under simple compression.

A still further object of the invention is to provide an oil heater furnace wherein the heat sources, or burners, are located in the upper portion of the arch of the inverted catenary whereby an essentially uniform downward radiation of heat from the furnace walls to the horizontal tubes located across the bottom of the furnace is obtained. This improved construction and arrangement of the elements, namely the location of the heat sources or burners for supplying heat initially to the chamber within the region of the crown of the inverted catenary furnace wall, and the horizontally arranged tubes adjacent the widest portion of the catenary wall, provides for distributed downward reflection of heat from said wall to the tubes. In addition to such provision for radiant heating of the tubes provision is made for supplying heat to the tubes by convection, by passage of the combustion gases over and between the tubes.

In the drawings:

Figure 1 is a vertical cross-section showing the inverted catenary form of the furnace with its rows of staggered oil heating tubes and the burners positioned in the upper part of the inverted catenary.

Figure 2 is a longitudinal section through the furnace illustrating the position of the rows of oil heating tubes in the lower part of the furnace and the plurality of lateral gas exhaust ducts.

Preferably the furnace consists of a non-metallic inverted catenary structure 1 composed of suitable refractory blocks or bricks 3 laid up in two layers 7 and 9 and supported along the longitudinal side edges on foundation walls 5, although a single course of masonry may be used instead of the double wall illustrated in the

drawings. In the preferred embodiment, the inner refractory layer 7 of the inverted catenary is slightly separated from the outer layer 9 by an intermediate air space 13 to take care of any differential expansion of the inner and outer walls of the inverted catenary. The exterior of the furnace may be covered with a layer of suitable insulating and weatherproofing material 11 which is loosely bonded to the outside of the catenary arch. This form of construction is entirely self-supporting and the masonry composing the inverted catenary is primarily in simple compression.

The ends of the inverted catenary arch are closed by refractory walls and, as shown in Figure 2, these end walls are independent of the catenary and, consequently, do not support any of the weight thereof while the abutting edges of the end walls and inverted catenary are provided with suitable expansion joints 17.

The furnace may be heated through the medium of a number of heat sources such as oil or gas burners 19 positioned through one or both of the end walls adjacent the upper or intrados portion or crown of the inverted catenary. Oil heating tubes 21 supported on transverse bridge walls 23 are arranged across the floor area near the base of the furnace, although sufficiently elevated thereabove to form a longitudinal plenum chamber 25 thereunder throughout the entire length of the furnace between the end walls thereof. As shown, the products of combustion are exhausted from the furnace through a plurality of lateral ducts 27, although it will be understood that the gases may be carried off through a longitudinal passage, or the like, to a suitable stack.

The radiantly heated oil tubes 21 are generally arranged in two spaced horizontal rows and in staggered relation, although, if desired, a bank of convection heated tubes may be positioned below the radiant heated tubes, whereby the hot descending gases flow evenly around the surfaces of the tubes to uniformly heat the same. The position of the upper burners 19 is such that the hot gases generated create a uniform downward radiation of heat from the furnace walls to the tubes over the whole tube area. After contacting the tubes, the gases pass into lower plenum chamber 25 and thence from the chamber through discharge ducts 27.

While the oil heating tubes 21 are illustrated as carrying diffusion baffles, as described and claimed in the copending applications of Otto C. Schauble, Serial Nos. 445,128 and 475,959, it will

be understood by those skilled in the art that any suitable form of baffle or diffusion device may be used to obtain a distribution of the flow of hot combustion gases for maximum transfer of heat to the tubing.

As before stated, the salient feature of this invention is the construction of an oil heater furnace composed substantially entirely of refractory material in the form of an inverted catenary that is self-supporting and places the entire construction in simple compression.

I claim:

1. In an oil heater including a furnace chamber, with oil tubing therein and burner means for supplying heat to the chamber; a continuous wall structure defining the roof and opposite sides of said chamber and formed of refractory blocks laid up to define an inverted catenary extending substantially to the bottom of the chamber, foundation means supporting said wall structure at the extremities of the catenary, said burner means being disposed to supply heat to the chamber initially within the region of the crown portion of the catenary for distributed downward reflection of the heat from the crown and sides of the catenary, and means supporting said oil tubing in a horizontal bank extending between opposite lower portions of the catenary to receive directly said downwardly reflected heat, said bank being spaced upwardly from the floor of the heater to afford therebeneath a plenum space within the heater, said space having an outlet, and the bank comprising a series of reaches of the tubing horizontally spaced to provide a series of intertube spaces for flow of combustion gases downwardly to the plenum space, whereby the bank will be heated by both convection and radiation.

2. In an oil heater including a furnace chamber with oil tubing therein and means for supplying heat to the chamber; a continuous wall structure defining the roof and opposite sides of said chamber and formed of refractory blocks laid up to define an inverted catenary with the extremities thereof substantially at the bottom of the chamber, foundation means supporting said wall structure at the extremities of the catenary, said heating means being disposed to supply heat to the chamber initially within the region of the crown portion of the catenary for downward reflection of the heat from the crown and sides of the catenary, and means supporting said oil tubing in a horizontal bank extending between opposite lower portions of the catenary to receive directly said downwardly reflected heat.
3. In an oil heater including a furnace chamber with oil tubing therein and means for supplying heat to the chamber; a continuous wall structure defining the roof and opposite sides of said chamber and formed of two spaced parallel courses of refractory blocks laid up to define an inverted catenary extending substantially to the bottom of the chamber, foundation means supporting said wall structure at the extremities of the catenary, said heating means being disposed to supply heat to the chamber initially within the region of the crown portion of the catenary for downward reflection of the heat from the crown and sides of the catenary, and means supporting said oil tubing in a horizontal bank extending between opposite lower portions of the catenary to receive directly said downwardly reflected heat.

CARL S. REED.
